UNITED STATES PATENT OFFICE.

CHARLES PUDDEFOOT, OF DETROIT, MICHIGAN, ASSIGNOR TO BRISCOE MANUFACTURING COMPANY, OF DETROIT, MICHIGAN, A CORPORATION OF MICHIGAN.

CORRUGATING-MACHINE.

SPECIFICATION forming part of Letters Patent No. 744,231, dated November 17, 1903.

Application filed December 30, 1902. Serial No. 137,113. (No model.)

To all whom it may concern.

Be it known that I, CHARLES PUDDEFOOT, a citizen of the United States, residing at Detroit, in the county of Wayne and State of Michigan, have invented certain new and useful Improvements in Corrugating-Machines, of which the following is a specification, reference being had therein to the accompanying drawings.

10 The invention relates to a machine especially designed for crimping or corrugating the bodies of sheet-metal pails or tubs; and it consists in the novel construction of the machine and in the peculiar arrangement and 15 combination of its various parts, as will be fully hereinafter described and illustrated.

In the drawings, Figure 1 is a plan view of the machine, and Fig. 2 is an end elevation thereof.

20 In constructing the machine a suitable bed A, similar to the ordinary lathe-bed, is preferably employed, upon which is mounted for longitudinal travel a carriage B.

C is a movable supporting member arranged upon the carriage for transverse movement, said member being adapted to slide in suitable ways a, formed upon the carriage.

D is a screw for operating the member C, swiveled in a bearing b on the carriage and 30 having a threaded engagement with the supporting member.

E represents a rotary head provided with a threaded spindle F, (shown in dotted lines in Fig. 1,) and G is a mandrel threaded upon 35 the spindle and carrying at its free end and fixed thereto a fluted roll H, preferably tapering in form.

I designates a frame secured in any suitable manner to the carriage B and provided 40 at its opposite ends, respectively, with a work-holder J, substantially circular in form, and an upright K. The holder described constitutes a support upon which the portion of the pail-body adjoining the bottom rests and is 45 provided with a bearing L therein, in which the free or outer end of the roll H is journaled.

P represents a roll-frame located upon the laterally-movable member C for rotary ad-

justment. As shown, this frame comprises a 50 head-section c, split, as at f, and arms d and e, carrying the bearings Q, in which the co-operating roll R is journaled. The head c of the frame engages over a stud g upon the member C and may be clamped thereto in 55 different position of adjustment by a screw-bolt h.

Upon the upright K is arranged an adjustable guide M, against which the upper edge of the pail or tub is adapted to bear. The 60 guide comprises a slotted arm h', secured by a bolt h² to the upright, a stud or spindle h³, projecting laterally from the arm, and a guide member h⁴, adjustable longitudinally upon the stud and adapted to be held thereto in different position of adjustment by a set-screw h⁵. The member just described is provided with an annular flange h⁶, against which the outer edge of the pail bears during the operation of the machine in the manner indicated in Fig. 1. 70

At the opposite end of the frame I and adjoining the combined work-holder and roll-bearing J described is a guide T, arranged upon the carriage for longitudinal adjustment. This guide comprises a swinging arm 75 U, pivoted to a slotted bracket V, which in turn is adjustably connected to the carriage by a bolt W.

X designates a stop on the bracket V, against which the arm strikes when in its 80 proper vertical position, and Y represents a guide-finger upon the arm adapted to bear against the pail-bottom.

The fluted rollers as shown are tapered of the same size and arranged, preferably, in a 85 horizontal plane. The central portion only of each roll is fluted, the flutes or ribs intermeshing. Each roll at its opposite ends has a plain portion or band i thereon, the portions upon the roll R being of less diameter than 90 the corresponding bands or portions upon the roll H, as shown.

S represents a pail mounted upon work-support J, with its outer edge supported by and bearing against the adjustable guide M, 95 the body of the pail being interposed between the corrugating-rolls. When properly arranged upon the support, the guide T is ad-

justed so that when the arm is swung upward into a vertical position the finger Y thereon will bear against the pail-bottom and hold the work in place. Motion being imparted 5 to the roll H through the agency of the spindle and its rotary head, the pail-body will be corrugated in the manner indicated, the central portion only of the pail-body being fluted, while the opposite ends thereof, which pass 10 between the plain portions of the rolls, are left smooth, forming the straight edges.

If it is desired to corrugate a pail of slightly-different size or having a slightly-different taper than the pail for which the rolls were 15 originally intended, it may be fluted by the same rolls by a proper adjustment of the pail-guides. The adjustment is effected by moving the member h^4 of the guide M laterally, either toward or away from its arm, according 20 to the size or taper, so as to bring the proper section of the pail-body between the rolls. After the guide M has been properly adjusted the guide T is correspondingly adjusted, so that the outer edge of the pail will be caused to 25 bear during the operation of the rolls against the flange h^3 . Where pails or tubs of considerably-larger size and taper are to be corrugated, the guide M is adjusted vertically as well as laterally and different rolls are sub- 30 stituted. The new rolls are arranged in operative relation by a proper adjustment of the transverse member C and the roll-frame P.

What I claim as my invention is—

1. In a sheet-metal-corrugating machine, 35 the combination of a driven fluted roll, a carriage adjustable longitudinally relative to said roll, a laterally-movable feed member upon the carriage, a frame adjustably mounted upon the feed member, and a fluted coöperating roll journaled in bearings upon said frame.

2. In a sheet-metal-corrugating machine, the combination with a fluted roll, of a carriage movable longitudinally relative thereto, a movable feed member upon the carriage, and a coöperating roll journaled in bearings 45 mounted for rotary adjustment upon said feed member.

3. In a sheet-metal-corrugating machine, the combination of a driven fluted roll, and a similar coöperating roll journaled at its ends in a support rotatably adjustable relative to the driven roll.

4. In a sheet-metal-corrugating machine, 55 the combination with a fluted roll mounted in stationary bearings, means for rotating the roll, a carriage movable longitudinally relative to said roll, a laterally-movable feed member upon the carriage, a frame mounted 60 upon the feed member for rotary adjustment, and a fluted coöperating roll journaled in bearings upon said frame, said coöperating roll being driven by the driven roll.

5. In a sheet-metal-corrugating machine, 65 the combination with a driven fluted roll mounted in stationary bearings, of a carriage movable longitudinally relative to said roll,

a laterally-movable feed member upon the carriage, a frame mounted upon the feed member for rotary adjustment, and a fluted coöperating roll journaled in bearings upon said frame. 70

6. In a sheet-metal-corrugating machine, the combination with a driven spindle, of a combined bearing and work-support having 75 an adjustable guide, a fluted roll secured at one end to the spindle and having its opposite end journaled in said bearing and support, and a coöperating fluted roll.

7. In a sheet-metal-corrugating machine, 80 the combination with a driven roll, of a work-support at one end thereof, an adjustable guide at the opposite end, and a coöperating roll operated by the driven roll.

8. In a sheet-metal-corrugating machine, 85 the combination with a driven fluted roll, of a work-support at one of the roll ends and an adjustable guide in proximity to the support, a laterally-adjustable guide member at the opposite end of said roll, and a fluted coöperating roll. 90

9. In a sheet-metal-corrugating machine, the combination with a driven fluted roll, of a work-support at one end thereof, an adjustable swinging guide-arm adjoining the support, a guide member at the opposite end of the roll arranged for vertical and longitudinal adjustment, and an adjustable coöperating fluted roll. 95

10. In a sheet-metal-corrugating machine, 100 the combination with a driven fluted roll, of a work-support at one end thereof, a guide at the opposite end of said roll comprising a vertically-adjustable arm carrying a spindle and a guide member adjustably arranged upon the spindle, and a coöperating fluted roll. 105

11. In a sheet-metal-corrugating machine, the combination with a driven fluted roll, of a work-support at one end thereof, a swinging 110 guide-arm for the work adjoining the support, a guide member at the opposite end of the roll, and a coöperating fluted roll.

12. In a sheet-metal-corrugating machine, the combination with a driven fluted roll, of a work-support at one end thereof, adjustable 115 guides for the work at the opposite ends of the roll, a coöperating fluted roll operated by the driven roll, and adjustable bearings in which said coöperating roll is journaled.

13. In a sheet-metal-corrugating machine, 120 the combination of a driven fluted roll, having projecting spindles at its ends, and a support for the spindles, said support being rotatably adjustable intermediate its ends.

14. In a sheet-metal-corrugating machine 125 the combination with a driven longitudinally-fluted roll, of a coöperating fluted roll, the adjoining ends of the rolls contacting and having a smooth uninterrupted surface there-around.

15. In a sheet-metal-corrugating machine, the combination with a driven fluted roll, of a coöperating fluted roll normally arranged at an angle to said driven roll, and means 130

whereby said coöperating roll may be shifted bodily in a transverse direction to adjust the same without changing the angularity of its position relative to said driven roll.

5 16. In a sheet-metal-corrugating machine, the combination with a driven fluted roll, mounted in suitable bearings, of a carriage movable longitudinally relative to said roll, a laterally-movable feed member upon the carriage, a frame mounted upon the feed member for rotary adjustment, and a fluted coöperating roll journaled in bearings upon said frame, said coöperating roll being normally arranged at an angle to the driven roll.

17. In a sheet-metal-corrugating machine, 15 the combination with a suitable supporting member, of a carriage longitudinally movable thereupon, a driven fluted roll mounted upon the carriage, a frame laterally movable upon the carriage, and a coöperating roll mounted 20 upon the frame.

In testimony whereof I affix my signature in presence of two witnesses.

CHARLES PUDDEFOOT.
